Specification for Design.

Patented Mar. 15, 1921.

Application filed June 24, 1919. Serial No. 306,482. Term of patent 14 years.

To all whom it may concern:

Be it known that I, EDWARD J. HOOPER, a citizen of the United States, residing at Stoughton, in the county of Norfolk and State of Massachusetts, have invented a new, original, and ornamental Design for Rubber Heels, of which the following is a specification, reference being had to the accompanying drawing, forming part thereof.

Figures 1 and 2 represent top and bottom perspective views of a rubber heel, showing my new design.

I claim:

The original design for a rubber heel, as shown.

EDWARD J. HOOPER.
